UNITED STATES PATENT OFFICE.

FREDERICK M. VOGEL, OF LYNN, MASSACHUSETTS, ASSIGNOR TO GENERAL ELECTRIC COMPANY, A CORPORATION OF NEW YORK.

HEATING DEVICE.

No. 839,343.

Specification of Letters Patent.

Patented Dec. 25, 1906.

Application filed April 22, 1905. Serial No. 256,860.

To all whom it may concern:

Be it known that I, FREDERICK M. VOGEL, a citizen of the United States, residing at Lynn, in the county of Essex and State of Massachusetts, have invented certain new and useful Improvements in Heating Devices, of which the following is a specification.

The present invention relates generally to heating devices, and more particularly to that type in which an electric resistance-conductor is employed as the heating element.

The general object of the invention is to improve the efficiency of devices of this sort, while at the same time maintaining a simple construction and a low cost of production.

To this end the invention comprises certain novel features of construction. One of these is a heat-distributing element or container of minimum heat-storage capacity, having its metal distributed about the heating unit so as to conduct the heat from all parts of the unit to the working face of the device with equal facility. The small storage capacity cuts down the usual time and energy losses due to heating and cooling a large mass of metal each time the device is used, and the novel disposition of the metal insures a minimum loss of heat due to radiation into the atmosphere.

Another feature of the invention resides in a novel construction of heating unit, which is put up in the form of a cartridge, so that it may be readily inserted into or withdrawn from its socket in the container or heat-distributing element for the purpose of renewal or repairs. This cartridge consists of an exterior envelop, in which is located an electric resistance-conductor, preferably consisting of a continuous helix of edgewise-wound conductor-ribbon, having its turns insulated from each other and the interior of the envelop.

In addition to the novelty of the heat-distributing element and the resistance-cartridge the invention also comprises certain other features and details of construction, which will be described more fully hereinafter and particularly pointed out in the appended claims.

Although the features of the invention are capable of use in various types of electric heating devices—such as stoves, griddles, water-heaters, chafing-dishes, and the like—I

have chosen to illustrate the same in an electrically-heated flat-iron and an electrically-heated frying-pan.

In the accompanying drawings, in which these embodiments of the invention are illustrated, Figure 1 is a perspective view of the flat-iron. Fig. 2 is a central longitudinal section of the same. Fig. 3 is a transverse section of the same; Fig. 4, a perspective view of the retaining-block, by which the resistance unit is held in place; Fig. 5, a rear view of the body of the flat-iron; Fig. 6, a longitudinal section of its weighted handle, while Figs. 7 and 8 illustrate in elevation and plan, respectively, the frying-pan construction; and Fig. 9 illustrates in perspective the resistance-cartridge employed as the heating unit.

Throughout the several views like characters refer to like parts.

In these two forms of the invention, 10 designates, generally, the heat-distributing element, and 11 the heating or resistance unit associated therewith. In each form the heat-distributing element is preferably integral and composed of metal throughout. The working face 12 of the element lies in 80 close proximity to the heating unit, so that at the points of nearest approach a very thin shell or layer of metal intervenes. This enables the heat of the unit to be applied practically directly to the work at those portions 85 of the working face 12 lying adjacent to the unit. In order to convey the heat from the other parts of the heating unit to the working face, a somewhat thicker layer or body of material is disposed over the other portions 90 of the unit. Thus the upper part of the unit is covered by the portion 13, which conforms in exterior outline to the adjacent surface of the unit, while a somewhat thicker mass of material 14 connects the portion 13 with the 95 working face. The amount of metal thus employed should be sufficient to furnish a conductive path of enough capacity to care for substantially all the heat radiated from the top and sides of the heating unit and to 100 convey it to the working face of the device. A larger mass is not only unnecessary but objectionable, since its only effect would be to increase the heat-storage capacity of the device. It will be seen that by this disposition 105 of the metal of the container a very efficient

- and quickly-responsive heating device is obtained. Obviously this construction is capable of use in many types of heating apparatus. When employed in flat-iron construction, the face 12 becomes the smoothing-face of the iron, and the weight necessary to the successful operation of the iron is provided by weighting the handle, while in the frying-pan construction the face 12 become the bottom of the pan, and the usual rim 12^a is provided, preferably by making the same integral with the heat-distributing member.
- In the case of the flat-iron the yoke 15 of the handle is secured to the upper side of the body of the iron in any suitable manner, as by a screw 16, and is prevented from rotating by the lug 16^a, which closely engages the opposite side of the yoke. The handle proper, 17, is included between the outer ends of the yoke 15 and comprises a central rod 18, extending through the weight 19, and an exterior covering 20, of fiber or other suitable heat-insulating material. In the case of the frying-pan the heat-distributing element may be supported in any desired manner, as by the legs 12^b, secured to lugs 12^c on the under side of the pan and connected by a central plate 12^d. A handle 12^e may also be provided.
- Obviously the heat-distributing element may be associated with a plurality of heating units by molding the metal so as to conform closely to the outline of each of the units in the manner disclosed in Fig. 7 and leaving the proper number of sockets or chambers for the insertion of the heating units.
- The heating unit 11 preferably takes the form of a cartridge, having an exterior envelop or tubular casing 21, consisting of copper or other heat-conducting material and having its ends spun down over a copper head 22, located at one end, and a porcelain, slate, or other insulating-head 23, located at the opposite end. Within this casing is located the resistance unit, which is preferably of the edgewise type, consisting of a continuous helical conductor 24, wound on edge, with its adjacent turns insulated from each other by some suitable insulation, such as a mixture of silicate of soda and clay, which in addition to insulating the turns binds the whole together in a rigid tubular structure, which may be readily inserted or withdrawn from the tubular casing when assembling or repairing the unit. The helical winding is insulated from the metal head of the casing by a heat-refractory insulating-disk 25 and from the tubular portion 21 of the casing by insulation 26, which preferably consists of a number of sheets of mica, which are closely fitted about the resistance-winding before it is inserted in the casing 21, so as to leave practically no space for the expansion of the mica, thereby greatly facilitating the trans-

fer of the heat from the conductor 24 through the mica to the casing 21 and thence to the heat-distributing element 10, since the mica when under compression is prevented from cleaving or "blistering," and thus providing a heat-insulating envelop, as is common where it is not maintained under pressure or otherwise held from lateral expansion. The winding 24 is connected to terminals 27 28 by leads 27^a 28^a, respectively, which extend through the insulating-head 23 of the cartridge structure. Since the lead 27^a must extend throughout the length of the helical winding 24, the latter is provided on its interior with mica or other insulation 29, so as to prevent a possible short circuit in case the lead 27^a should become displaced.

Obviously the resistance cartridge or unit may be held in place in any suitable manner. In the flat-iron, where the body of the iron—*i. e.*, the heat-distributing element—has a socket opening rearward, the heating unit is preferably held in place by a wedge-shaped block 30, which fits into vertical grooves 31, located at the open end of the socket. As clearly shown in Fig. 4, this block is provided with openings for the passage of the terminals 27 28, which extend upward therethrough. These terminals are threaded at 32 for the reception of small nuts 33, which bear against the upper side of the wedge-block 30 and prevent its removal, and consequently the removal of the unit 11. In this way very small nuts serve to keep all the parts in place. Obviously in service the terminals 27 and 28 are connected to some suitable source of current-supply, and the passage of the current through the resistance-conductor 24 produces the desired heat energy, which is transmitted, as previously indicated, to the working surface 12 of the heating device.

The construction hereinbefore described has a number of advantages that are considered decisive in practical operation:

First. The heating unit being removable from the body to be heated and all the units being made of a definite size permits uninterrupted work in case of any damage to the resistance which would prevent a normal action. A defective unit may therefore be quickly removed and inspected and a spare unit put in its place if the damage require expert attention.

Second. The thin wall of metal between the heating unit and the work enables the working surface of the device to be brought almost instantly to the temperature necessary for use. In such devices, particularly flat-irons as commonly constructed, there is a large mass of metal around the unit which must be heated before the working surface is at a temperature fit to be used. This consumes time. In the device of my construction the instrument may be used almost im-

mediately on the current being turned on, because there is almost no storage capacity for heat by reason of the thin wall of metal between the unit and the work. Besides 5 this there is an important incidental advantage in that the instrument cools off very quickly after the current is interrupted by reason of this same small storage capacity for heat. Consequently the room in which 10 the work is being conducted can be maintained at a more comfortable temperature for the operator, since very little heat is thrown off into the atmosphere, almost all of it being drawn into the work, and when 15 the service is interrupted and the current cut off the device quickly cools.

Third. By reason of the small mass of metal around the unit and the excellent heat-conductive relation between the working surface and all parts of the heating unit the heat is supplied at a much more uniform rate to the work. This is of great advantage in flat-irons, where some parts of the goods may be more damp than others, and consequently 25 can stand with advantage a higher heat.

Where there is a large mass of metal, the working face is lowered in temperature when a larger proportion of heat is absorbed by the work, and the thermal lag, so to speak, prevents 30 the highly-heated surface of all parts of the resistance unit from responding to maintain the temperature at the work-surface. With my construction, however, the intervening mass of metal is so small that its 35 thermal lag is almost *nil*, and the heating unit can respond very quickly to keep up the temperature at the working surface, irrespective of the character of the goods being operated upon or of the condition as to damp- 40 ness of different parts of the goods.

It will be apparent to those skilled in the art that the number of heating units employed and their relative arrangement might be varied and that other modifications and 45 alterations might be made without departing from the spirit and scope of my invention. I therefore do not wish to be limited to the specific matter illustrated and described, but aim to cover by the terms of the appended 50 claims all such alterations and modifications.

What I claim as new, and desire to secure by Letters Patent of the United States, is—

1. An electric heating device comprising a metal container, an electric resistance unit 55 located within said container, and a layer of mica closely surrounding said unit and held from expansion in the direction of cleavage.

2. A resistance-cartridge for electric heating devices comprising an exterior shell, an 60 electric resistance unit closely fitted within said shell, and an intervening layer of mica between said unit and said shell held from cleavage expansion by the close fit of said unit within said shell.

65 3. A resistance-cartridge for electric heat-

ing devices comprising an exterior shell, a coil of electric resistance-conductor closely fitted within said shell, and an intervening layer of mica between said coil and said shell held from cleavage expansion by the close fit 70 of said coil within said shell.

4. A resistance-cartridge for electric heating devices comprising an exterior tubular shell, a coil of resistance-ribbon wound on edge into a continuous helix, and insulation 75 between the turns of said ribbon and a layer of mica between said ribbon and said shell.

5. A resistance-cartridge for electric heating devices comprising an exterior tubular shell, a coil of resistance-ribbon wound on 80 edge into a continuous helix and closely fitted within said shell, insulation between the turns of said helix, and an intervening layer of mica between the exterior of the helix and the interior of said shell held from expansion by 85 the close fit of said helix within said shell.

6. A resistance-cartridge for electric heating devices comprising an exterior tubular casing of good heat-conductive material, a resistance-winding located within said casing 90 and insulated therefrom by a layer of mica, and terminals for said winding extending from one end of said casing.

7. A resistance-cartridge for electric heating devices comprising an exterior tube and a 95 resistance-ribbon wound on edge into a continuous helix located within said tube, insulation between the adjacent turns of said helix and between said helix and said tube, heads located at the opposite ends of said tube, and 100 terminals for said winding extending through one of said heads.

8. An electric flat-iron comprising a metal body provided with a smoothing-face, an electric resistance unit located in heat-conductive relation thereto, and a weighted handle secured to said body. 105

9. An electric flat-iron comprising a metal body provided with a smoothing-face, an electric resistance unit located in heat conductive relation to said face, and a weighted handle secured to said body provided with a covering of low heat conductivity. 110

10. An electric flat-iron comprising a metal body provided with a smoothing-face, an interior chamber adjacent to said face, an electric resistance unit located in said chamber, terminals for said unit extending through the open end of said chamber, and an insulating-block for holding the unit in place provided 115 with openings for the passage of said terminals. 120

11. An electric flat-iron comprising a metal body provided with a smoothing-face, an interior chamber adjacent to said face, an electric resistance unit located in said chamber, terminals for said unit extending through the open end of said chamber, an insulating-block for holding the unit in place provided with 125 openings for the passage of said terminals, 130

and nuts threaded on said terminals and bearing against said block to hold the same in place.

12. An electric flat-iron comprising a metal body provided with a smoothing-face, an interior chamber adjacent to said face, an electric resistance unit located in said chamber, terminals for said unit extending through the open end of said chamber, laterally-extending grooves in said body adjacent to the open end of said chamber, and a removable insulating-block fitted in said grooves for holding the resistance unit in place.

13. An electric flat-iron comprising a metal body provided with a smoothing-face, an interior chamber adjacent to said face, an electric resistance unit located in said chamber, terminals for said unit extending through the open end of said chamber, grooves in said body adjacent to the open end of said chamber, and extending laterally thereto, a removable insulating-block fitted in said grooves

for holding the resistance unit in place, terminals for said resistance unit extending through openings in said block, and nuts 25 threaded on said terminals and bearing against said block to hold the same in place.

14. An electric flat-iron comprising a metal body, having small heat-storage capacity, an electric resistance located in heat-conductive relation thereto, and a weighted handle secured to said body.

15. An electric flat-iron comprising a metal body, provided with a smoothing-face and having a small heat-storage capacity, an electric resistance unit located adjacent to said face and in heat-conductive relation thereto, and a weighted handle secured to said body.

In witness whereof I have hereunto set my hand this 20th day of April, 1905:

FREDERICK M. VOGEL.
